(57) **CLAIM**

The ornamental design for a hot air gun, as shown and described.

DESCRIPTION

The file of this patent application contains at least one drawings/photograph executed in color. Copies of this patent with color drawing(s)/photograph(s) will be provided by the Patent and Trademark Office upon request and payment of the necessary fee.

FIG. 1 is a right side elevational view of a hot air gun showing our design;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a front perspective view thereof.

The green, blue and black colors shown in the drawings form part of the design.
